(57) **CLAIM**

The ornamental design for a three-panel triage card, as shown and described.

DESCRIPTION

The patent or application file contains at least one drawing executed in color. Copies of this patent or patent application publication with color drawings(s) will be provided by the Office upon request and payment of the necessary fee.

FIG. 1 is a view from the front of a 3-panel triage card showing our new design.

FIG. 2 is a view from the back of the 3-panel triage card showing our new design.

FIG. 3 is a front plan view of the first of the 3 panels of the triage card showing our new design.

FIG. 4 is a back plan view of the first of the 3 panels of the triage card showing our new design.

FIG. 5 is a front plan view of the second of the 3 panels of the triage card showing our new design.

FIG. 6 is a back plan view of the second of the 3 panels of the triage card showing our new design.

FIG. 7 is a front plan view of the third of the 3 panels of the triage card showing our new design; and,

FIG. 8 is a back plan view of the third of the 3 panels of the triage card showing our new design.

The broken lines at the edges of the individual panels in FIGS. 1–8 depict the fold lines and form no part of the claimed design. All other broken lines are applied surface indicia and form part of the claim.
